(57) **CLAIM**

The ornamental design for a tire, as shown and described.

DESCRIPTION

FIG. 1 is the front elevational view of a tire, for which the other sides, include rear, top and bottom elevational views being identical thereto;

FIG. 2 is a left side elevational view thereof;

FIG. 3 is a right side elevational view thereof;

FIG. 4 is an enlarged fragmentary top elevational view thereof; and,

FIG. 5 is a perspective view of a tire showing the new design, it being understood that the pattern repeats uniformly throughout the circumference of the tread.
